UNITED STATES PATENT OFFICE

2,550,846

GOLF CLUB

Charles Stanley Milligan, Hamilton, Ontario,
CanadaApplication July 14, 1948, Serial No. 38,667
In Great Britain July 5, 1948

6 Claims. (Cl. 273—77)

1

The present invention relates to golf clubs, and more particularly to golf clubs which impart a spin to the golf ball at impact by utilizing air currents developed by the particular shapings of the golf clubs.

Consideration has been given to aerodynamic laws in the past as it has been proposed to streamline the shaft and/or the head of the club to reduce the air resistance to movement of the club but, so far as I am aware, the prior designers of golf clubs have not appreciated or at least have not taken advantage of the fact that aerodynamic forces of substantial magnitude are developed by a golf club as it moves into contact with the ball. At impact, the club head may be travelling at up to about 126 miles per hour, i. e. 184.8 feet per second, and it has long been recognized that the club meets with considerable air resistance at speeds of this order.

Objects of this invention are to provide golf clubs with heads of such shape as to utilize the air currents developed by the rapidly moving club head to impart a spin to the ball. Objects are to provide golf clubs having heads of novel shape which reduce the air resistance to high speed travel of the club head and which develop air currents which rush past the ball to impart a spin to the same as it leaves the face of the club head. More specifically, objects are to provide club heads which are "relieved" by streamlined recesses at the top or at the bottom surfaces of the head to develop air currents over or beneath a ball to impart a back spin or a top spin respectively.

These and other objects and the advantages of the invention will be apparent from the following specification when taken with the accompanying drawings in which:

Fig. 1 is a fragmentary front elevation of a driver embodying the invention;

Figs. 2 and 3 are, respectively, a perspective view of the bottom of the driver; and a vertical section through the same on line 3—3 of Fig. 1;

Fig. 4 is a front elevation of the head of a brassie embodying the invention;

Fig. 5 is a plan view of the same;

Fig. 6 is a vertical section through the brassie on line 6—6 of Fig. 4;

Fig. 7 is a fragmentary front elevation of a driver having a sole plate which is shaped to impart the desired spin to the golf ball;

Fig. 8 is a section on line 8—8 of Fig. 7;

Fig. 9 is a fragmentary front elevation of a brassie having a top plate in which the shallow groove is formed;

2

Fig. 10 is a section on line 10—10 of Fig. 9;

Fig. 11 is a front elevation of an iron club provided with a top recess for imparting back spin to the ball; and

Fig. 12 is a section on line 12—12 of Fig. 11.

In Figs. 1 and 2 of the drawing, the reference numeral 1 identifies the head of a driver having a shaft 2 which may be of conventional circular cross-section or may be streamlined to reduce air resistance. The lower surface of the club head 1 is provided with a relatively wide and shallow groove 3 which is streamlined to avoid turbulence in the air current through the same when the club head is moving at high speed, i. e. the groove flares smoothly inwardly from its inlet to a region of minimum width at about the center of the lower surface of the head 1 and then flares smoothly to an exit at the rear of the club head which is preferably somewhat wider than the entrance to relieve compression and insure the quicker dispersion of the air under compression. The axis or center line of the groove 3 is, of course, in line with the intended path of travel of the golf ball. The club head may be, and preferably is, provided with conventional metal sole plates 4, 4' at opposite sides of the groove 3. As shown in Fig. 3, a driver having a head 1 provided with a groove 3 may have its striking face at a slightly steeper angle than normal to increase the air compression above the ball.

The method of operation of the novel driver will be apparent from a consideration of Fig. 3. A lower portion of the ball is in line with the groove 3 at the instant of impact and top spin is imparted to the ball by the air current, indicated by arrows *a*, which flows through the groove 3 and constitutes a drag or frictional resistance to forward movement of the bottom of the ball.

40 The drag action is developed even though the ball may be topped by the player, and it is supplemented by the air compressed against the upper portion of the striking surface 5.

45 For a brassie or spoon, having a head 7 on a shaft 8, back spin may be imparted to the ball by aerodynamic action by providing a streamlined groove or recess 9 in the upper surface of the club head 7. As shown in Fig. 6, a back spin will be imparted to the ball by the air current, indicated by arrows *b*, which results from the high speed travel of the club head 7 and flows over the top portion of the ball.

It is convenient and economical to provide the 50 spin-imparting grooves in shaped plates of metal,

plastic materials or wood which are secured to the main body of a club. Such shaped plates may be employed in the manufacture of new clubs, or may be used to convert existing clubs into embodiments of this invention.

In the case of a driver, as shown in Figs. 7 and 8, the body portion of a club head 10 on a shaft 11 has a flat lower surface to which the flat upper surface of a sole plate 12 is secured by screws 13, the lower surface of the sole plate being provided with a shallow streamlined groove 14. In like manner, as shown in Figs. 9 and 10, a plate 15 with a shallow streamlined groove 16 may be secured by screws 17 to the head 18 of a brassie.

As shown in Figs. 11 and 12, the invention may be applied to an iron club head 19 by cutting or otherwise shaping the top surface to provide a shallow groove 20. The forward edge 21 of the top surface of the club head is preferably parallel to the lower edge 22 of the striking face, i. e. the depth of the striking face at the hosel is made equal to the depth at the toe of the club. This relationship affords the desired aerodynamic flow over the top surface of the ball and has the further advantage that the parallel arrangement of the top and bottom edges 21 and 22 facilitates the proper alignment of the club head with respect to the ball.

It is to be understood that the invention is not limited to the particular constructions herein shown and described, and that modifications which may occur to those familiar with the design and construction of golf clubs fall within the spirit and scope of the invention as defined in the following claims.

I claim:

1. A golf club comprising a shaft and a striking head, said striking head having upper and lower surfaces, and one of said surfaces being provided with a recess in line with the desired path of travel of a ball for establishing an air current to impart a spin to the ball; said recess being streamlined with a minimum width and depth at an intermediate section, and the exit of the recess at the rear of the club head being wider than the entrance of the recess.

2. A golf club as recited in claim 1, wherein said striking head comprises a body portion having a flat surface, and a shaped plate having a flat

surface secured to the flat surface of said body portion, the opposite surface of said shaped plate being provided with said streamlined recess.

3. A golf club head as recited in claim 2, wherein in said plate is secured to said body portion to form the lower surface of the club.

4. A golf club head as recited in claim 2, wherein in said plate is secured to said body portion to form the upper surface of the club.

5. A golf club comprising a shaft and a striking head, said striking head having a body portion with upper and lower surfaces, one of said surfaces being flat, and a shaped plate having a flat surface secured to the flat surface of said body portion, the opposite surface of the shaped plate being provided with a recess extending in line with the desired path of travel of a ball for establishing an air current to impart a spin to the ball, said recess being streamlined with a minimum width and depth at an intermediate section, and the exit of the recess at the rear of the club head being wider than the entrance of the recess.

6. A golf club comprising a shaft and a striking head with an upper and a lower surface, the upper surface being provided with a streamlined recess extending in line with the desired path of travel of a ball for establishing an air current to impart a back spin to the ball, said recess having a minimum width and depth at an intermediate section, and the exit of the recess at the rear of the club head being wider than the entrance of the recess.

CHARLES S. MILLIGAN.
